(57) **CLAIM**

The ornamental design for a cradle for wireless remote control device, as shown and described.

DESCRIPTION

FIG. 1 is a perspective view of the cradle for wireless remote control device;

FIG. 2 is a right side view of the cradle for wireless remote control device;

FIG. 3 is a left side view of the cradle for wireless remote control device;

FIG. 4 is a top view of the cradle for wireless remote control device;

FIG. 5 is a bottom view of the cradle for wireless remote control device;

FIG. 6 is a front view of the cradle for wireless remote control device; and,

FIG. 7 is a back view of the cradle for wireless remote control device.

The broken lines in the figures depict portions of the cradle that form no part of the claimed design.
